(57) **CLAIM**

The ornamental design for a knob for cooking utensil, as shown and described.

DESCRIPTION

FIG. 1 is a top and side perspective view of a knob for cooking utensil, showing my new design;

FIG. 2 is a side elevational view thereof;

FIG. 3 is a top plan view thereof;

FIG. 4 is a bottom plan view thereof;

FIG. 5 is a view thereof from the right of FIG. 2, the view from the left of FIG. 2 being a mirror image thereto; and,

FIG. 6 is a view thereof showing the side opposite that shown in FIG. 2.
